(57) **CLAIM**

The ornamental design for a head for a dart, as shown.

DESCRIPTION

FIG. 1 is a perspective view of a head for a dart, showing my new design, illustrated in a condition assembled on a wing portion of a dart;

FIG. 2 is a top plan view of the dart of FIG. 1;

FIG. 3 is a left side elevational view of the dart of FIG. 1;

FIG. 4 is a bottom plan view of the dart of FIG. 1;

FIG. 5 is a right side elevational view of the dart of FIG. 1;

FIG. 6 is a front elevational view of the dart of FIG. 1; and,

FIG. 7 is a rear elevational view of the dart of FIG. 1.

The portions of the drawings that are shown in dashed lines are environment and are not part of the claimed design.
